DESIGN FOR A DRESS

Irene Welch, New York, N. Y.

Application October 19, 1937, Serial No. 72,301

Term of patent 3½ years

To all whom it may concern:

Be it known that I, Irene Welch, a citizen of the United States, residing in the county of Kings, city and State of New York, whose post office address is 3382 12th Avenue, Brooklyn, New York, have invented a new, original, and ornamental Design for a Dress, of which the following is a specification, reference being had to the accompanying drawing, constituting a part thereof.

Fig. 1 is a front view of the dress.

Fig. 2 is the rear view of the dress as shown in Fig. 1.

The design is characterized by the gathered neckline below the collar in combination with the pointed bows on the collar and arched girdle and by the filled-in surplice overlap on the back, all as shown.

I claim:

The ornamental design for a dress, substantially as shown and described.

IRENE WELCH.
